TEXTILE CLEANING APPARATUS

Frederick E. Snowden, Los Angeles, Calif., assignor, by direct and mesne assignments, to Sunbrite Corporation, Ltd.

Application December 28, 1927, Serial No. 243,002

15 Claims. (CL. 68—38)

My invention is in a textile cleaning apparatus and in the method of cleaning and handling the cleansing fluids.

An object of my invention is a textile cleaning apparatus and method of handling the cleansing fluid by which the same fluid may be utilized over and over again in cycles, in which the dirty fluid is strained, then evaporated and condensed and then is in a condition for re-using. With this main object, I have a certain refinement, such as if the condensed fluid is not clean enough for re-using, it is passed into a tank for fluid to be re-cleaned and then when convenient may be put through the filter and again distilled.

A general object of my invention is a cleaning machine and method in which the operation is carried on without the use of pumps or other moving parts, except the operation of the various valves and the rotary drum in the cleaning machine.

Another object of my invention is in a textile cleaning apparatus and method, in which air is forcibly blown through the textiles, such as garments, before cleaning, this acting to blow dust and the like out of the garments and dry any water which may be in the materials to be treated. After this, the materials are subjected to a cleaning action by a cleansing fluid and subsequently thereto the materials being handled are again subjected to an air blast under pressure, this being preferably heated, and functioning to carry off the vapors of the cleaning fluid, thereby drying the fabric or garments, and at the same time deodorizing the same.

A further object of my invention is in utilizing a filter immediately to cleanse fluid which has been utilized in cleansing a batch of textile material, and in order to dry this material a blast of air is blown through the cleaning machine and the vapors taken up by the air are condensed and flow into storage tanks.

Another object of my invention is in mounting a series of tanks and the piping connected therewith in a construction which will occupy a comparatively small amount of floor space and with a short system of piping from the tanks to the cleaner, and entirely eliminates the use of pumps or moving parts.

A further object of my invention is to blow air through the cleaning machine and through the articles being cleansed before they are subjected to the cleansing fluid, this being to blow the dust out of the articles, and after the cleaning operation, air preferably heated is blown through the articles, carrying away the mois-

ture retained in such articles, this moisture being condensed.

Another detail object of my invention is in passing the cleansing fluid through a screening or filtering trap to collect articles loosened from the garments being treated, such as buttons, matches, coins, etc.

Another object of my invention is to cleanse textile fabrics by a non-inflammable fluid such as carbon tetrachloride, and in connection with the installation utilizing a hose with a suitable reel so that a supply of fire extinguisher is always ready at hand in case of fire in the cleaning establishment.

In constructing my invention as to the apparatus, I build a suitable frame-work or tower structure and on the top of this I have a condensing tank with piping coils immersed in water. One set of these piping coils is connected with an evaporator, heated in any suitable manner, this evaporator distilling the previously used fluid. Below the condensing tank there is a first storage tank in which the condensed fluids from the first set of condensing pipes run. This storage tank is then connected to a main supply tank immediately therebelow, and by another connection leads to a still lower tank for dirty condensate. At the bottom of the tower there is a screen or separator trap for cleaning the fluid which has been subjected to the cleaning operation.

Situated to one side of the tower there is a cleaning machine preferably having a rotary drum in the interior thereof, in which the articles are placed, and this machine is supplied from the main supply tank. A drain leads from the cleaner to the screening and filter trap and a connection is made from the screening trap to the evaporator.

In connection with the cleaning machine I utilize an air blower which is first used to blow air through the articles to be cleaned while these are dry, before the entrance of the cleaning fluid, this being to blow dust out of garments and the like. The air first blown through the dusty garments is blown out through a bubbling receptacle having water, and catches the dust and other dirt. After the cleaning, a preferably heated air blast is used which evaporates the residual cleaning fluid in the garments. This air is then passed through a condensing box in the main condensing tank, and the cleaning fluid carried by the air is condensed therefrom, flowing into the trap tank.

The main supply tank and the dirty distilled

fluid tank are connected to condensing coils in the main condensing tank so that any vapors which rise from these tanks will be condensed. The piping connection has an exhaust to the air so that in the filling and emptying of the tanks there may be a to and fro flow of air, the air being indrawn and discharged to the external atmosphere.

5 My invention in its various aspects is illustrated in the accompanying drawings, in which:

10 Figure 1 is an end elevation of the cleaning apparatus.

Fig. 2 is a side elevation.

15 Fig. 3 is an end elevation taken in the direction of the arrow 3 of Fig. 1 or 4 of the cleaning machine.

Fig. 4 is a side elevation of the cleaning machine taken in the direction of the arrow 4 of Fig. 3 with certain parts broken away.

20 Fig. 5 is a vertical section on the line 5-5 of Fig. 6 in the direction of the arrows through the screening trap.

Fig. 6 is an end elevation of the trap taken in the direction of the arrow 6 of Fig. 5.

25 Fig. 7 is a plan of the trap taken in the direction of the arrows 7 of Fig. 5 or 6.

Fig. 8 is an end elevation of the condensing tank taken in the direction of the arrow 8 of Fig. 9.

30 Fig. 9 is a horizontal section of the condensing tank taken on the line 9-9 of Fig. 10 in the direction of the arrows showing the cover removed.

Fig. 10 is a vertical section of the condensing tank taken in the direction of the arrows 10-10 of Fig. 8 in the direction of the arrows.

35 Fig. 11 is a vertical section through the hose reel and showing the connection of the hose to one of the tanks.

40 Fig. 12 is a diagrammatic lay-out of my invention showing the various tanks, the coils and the piping connection therebetween.

45 Referring to the general lay-out as disclosed in Figs. 1 and 2, this illustrates a suitable frame work or a tower structure 11 which has posts 12 and cross framing members 13, these being placed in suitable positions. At the top of the tower there is a condenser box 14, the details of which are given hereunder. Immediately below the condenser there is what may be termed a first or run tank 15 to contain the fluid run from the still after condensing. Below the tank 15 there is a main storage tank 16 which may be designated as the clear fluid tank. This tank has a large capacity. The next lowest tank may be designated as a trap tank 17 and is of a comparatively small capacity and is designed to receive and store fluid which is too dirty after being distilled or condensed to use in the cleaning machine.

50 The cleaning machine is designated generally by the numeral 18 and is driven by a power plant 19 which may be of any suitable character and is illustrated as of standard equipment. A flight of steps 20 are utilized to give access to this cleaning machine, such machine having a cover 21 to handle the articles being cleansed. At the base of the tower and below the level of the cleaning machine to receive the run off therefrom there is a screening trap 22. This trap is connected in the manner hereunder set forth to a still or evaporator 23, this latter being of any suitable character and having a furnace chamber 24 at the base and a hood 25 above the still to collect the heated air from the still and divert this from the tanks.

55 75 On top of the tower I mount an air cooler and

humidifier 26; this has a convenient mounting for this machine which may be constructed in accordance with my patent application, Serial No. 200,055, filed June 20, 1927.

The details of the various parts are substantially as follows:

The condenser box 14 is illustrated particularly in Figs. 8, 9, and 10 and in this is shown a main coil of pipes 30 connected to a header 31, this header being connected to a lead pipe 32 from the still. This coil has a discharge end 33 connected up as hereunder set forth. In addition to this coil there is a second or smaller coil 34 which has an inlead pipe 35 and a trap 36. A third condensing coil 37 has an inlead pipe 38 and 15 a trap 39 (note particularly Figs. 9 and 12).

Situated in the condenser box 14 there is also a vapor trap box 40 which has an air inlet pipe 41 at the top. A series of baffle plates 42 are positioned in this air trap forming zigzag passages, and there is an air outlet 43 which leads upwardly to a stack 44 having a cowl 45 thereon (note Figs. 1, 8 and 12). A circulation of water through the condensing box is obtained by the pipes 46 and 47 connected to any suitable 25 water supply, this condensing box being maintained substantially full of water, at the required temperature to condense the vapors from the still and the vapors entering the coils 34 and 37, and the vapors carried by the vapor to the air 30 trap box 40.

The cleaning machine designated generally by the numeral 18 is constructed substantially as follows, having reference particularly to Figs. 1, 3 and 4:

35 This machine in its main characteristics is very much like standard cleaning machines having a shell or casing 50 with a rotary drum 51 therein, this drum being utilized for the articles to be cleaned and having a series of perforations, baffles, etc. therein, access being had to the drum through the cover 21, the drum also having a suitable cover. A main liquid supply pipe 52 is connected to the shell, discharging therein at a high level, and the shell is provided with an 45 inclined bottom 53 having a discharge pipe 54. Adjacent the base of the shell and below the drum there is an air pipe 55 having a series of perforations, and at the top of the casing there is an air outlet pipe 57, the air system being as 50 hereunder set forth.

The fluid trap designated generally by the numeral 22 is constructed substantially as follows: This comprises a casing having flat side walls 60, a vertical end wall 61, an inclined bottom 62, a short vertical wall 63 and a cover wall 64. The pipe 54 draining from the cleaning machine leads to a valve 65 and through a pipe 66, discharging into the trap; there being a cage 67 therein formed of screening material to trap 60 any large articles which may be discharged. In the trap there is an inclined screen 68 made of foraminous material of fine mesh and preferably having a filtering layer 69 formed of chamois or other suitable filtering medium. This 65 screening is insertable and removable after removing a large hand hole cover 70. The fluid after being filtered is discharged through a pipe 71 and to drain the collected dirt there is a drain pipe 72 having a valve 73 therein. This may 70 drain into suitable buckets or the like.

The reel designated generally by the numeral 75 made of standard character, and is connected to a pipe 76 leading to one of the tanks for the cleansing fluid as hereunder mentioned, the reel 75

having a considerable length of hose 77 coiled thereon, and this having a suitable rotatable joint so that in reeling the hose out or in, it always forms a fluid connection with the tank, this being substantially a standard unit.

5 The manner of operation of my cleaning apparatus and the piping connections is substantially as follows, having reference particularly to the diagrammatic layout of Fig. 12 and Figs.

10 1 and 2:

The main or clear fluid tank 16 in the initial operation may be filled through a hand hole 80, or this may be filled by pumping the cleansing fluid therein. This fluid is discharged through the base 81 from which leads to a large discharge pipe 82 having a valve 83 therein. This leads to piping 52, discharging into the cleaning machine. After the cleaning operation the dirty liquid flows out through the pipe 54 which, as above mentioned, is controlled by the valve 65 and through the pipe 66. The liquid flows into the separating trap 22 where it is cleansed by filtering, the effluence flowing out by the pipes 71 and through a valve 84, then through a check valve 85 and a pipe 86 into the still 23. The vapors from the still are collected in the dome 87 and flow upwardly through the vertical lead pipe 88 which connects to the main condensing coil 30 in the condenser box 14, the connection, as above mentioned, being through the header 31. (Note Fig. 12).

The condensate in the coils 30 flows outwardly through the pipe 31 and then downwardly through a pipe 89. This pipe has a trap 90 thereon and a vertical lead 91 therefrom connecting into the first tank 15 which, as above mentioned, receives first the run from the still. All of the tanks are provided with liquid level gauges as indicated at 92 and if this liquid is sufficiently clear to be utilized again, it is discharged through the pipe 93 connected to the base of the first tank 15 and leads through a pipe 94 to the top of the main or clear fluid tank 16, there being a control valve 95, and in which case the fluid is used over again for cleaning,—this completing one cycle.

If the condensed fluid in the first tank 15 is too dirty to be utilized for cleaning, it is discharged through the pipe 96 having a control valve 97 leading from the tank 15, this pipe 96 connecting to the trap tank 17 adjacent the base of the tower connected to the base thereof. This trap tank also has a connection by a pipe 97 having a valve 98 therein with the discharge outlet 81 of the main tank 16, this latter pipe also leading to the bottom of the trap tank 17.

The liquid from the trap tank 17 is discharged from the outlet 99 through a pipe 100 controlled by a valve 101. This leads into a junction 102 with the pipe 66 leading to the trap separator 22. Therefore, if the liquid, as above mentioned, is found to be too dirty in either of the tanks 15 or 16, or both, it may be discharged into the trap tank 17 and then at any suitable time passed again through the trap separator 22, and thence again through the still, repeating the operation until all of the cleansing fluid is sufficiently clear to be utilized.

In the flow of the liquid from the tanks it is necessary to take care of the air flow in and out of such tanks, and any vapor of the cleansing fluid which may be developed in the tanks. Therefore, a vapor pipe 105 is connected to the top at 106 of the first tank 15 having the run of the still. This pipe leads upwardly and connects to

the pipe 35 of the second condensing coil 34 in the condensing box 14. As above mentioned there is a trap 36 which is connected by the junction 106 with the pipe 105, and a second trap 107 is also connected to the junction and has at its discharge end an up-leading pipe 108. This is connected by a T junction 109 to an air pipe 110 connecting to the vapor vent pipe 111, which latter pipe extends upwardly into the cowl 45. The vapor vent pipe 111 has a connection 112 with a trap 113 therein, and a connection 114 to the junction 115 of the discharge pipe 33 for the condensate from the main or first condenser 30 and the condensate discharge pipe 89.

The action of this vapor connection from the top of the first tank 15 is substantially as follows:

Any vapors of the cleaning fluid flow upwardly in this tank and if the pressure is slight this vapor passes the junction 106 through the inlet pipe 35 to the condensing coil 34, the condensate filling the trap 36, and when such trap is filled, the condensate overflows and returns by the pipe 105 again to the tank 15. If the pressure of the vapor is sufficiently great it forces these vapors through the trap 107 from the junction 106, and upwardly through the pipe 108, the junction 109, the pipe 110, and vapor vent pipe 111; but as a certain amount of the vapors become condensed when in operation, there is always a certain amount of condensed vapors in the trap 107 forming, therefore, a seal, ordinarily preventing escape of the vapor, unless the pressure is sufficiently excessive to force the vapors out. It will thus be seen that the above connection takes care of the vapors developed in the top or first tank 15.

The main or clear fluid tank 16 has a vapor outlet 120 which leads through a pipe 121, and the junction 122 to the intake pipe 38 of the condensing coils 31, these coils discharging into a trap 123 which is also connected to the junction 122. There is a trap 123 connected to the junction 122 and an outlet pipe 124 from such trap. This connects to the junction 109, the lead pipe 112 and to the vapor vent 111.

The action of this vapor connection is substantially the same in principle as that described in connection with the first tank 15. When this tank is filled through the hand hole in the initial operation, the hand hole allows escape of the air, but after the tank is in operation, with the hand hole sealed, and it is desired to fill it by pumping this vapor connection pipe 121 allows escape of the air.

The air blowing system for cleaning the clothes initially and for removing the residual cleansing fluid and drying is substantially as follows:

An air blower is indicated by the numeral 125 and is mounted at a suitable place on the frame of the machine, this being preferably driven by an electric motor. The air from this blower is discharged through an electric air heater 126 which may be controlled as desired, and the temperature of the discharged air read on a thermometer 127. This discharged air leads through a valve 128, the air pipe 56, and enters the perforated pipe 55 in the bottom of the cleaning machine. In the first operation for cleansing, the air after passing through the cleaning machine is discharged by the pipe 57 controlled by the valve 129. This air laden with dust is blown downwardly through an air discharge pipe 130 into the bubbling or water sealed receptacle 131 which collects the dust in the water.

After the cleaning operation, when it is desired to remove residual cleansing fluid from the ar-

ticles in the cleaning machine and to dry them, the valve 129 is operated to discharge the air upwardly in the air pipe 132 which leads to the vapor trap 40 immersed in the condensing water in the condensing box 14. The air circulates through this vapor trap, the vapors being condensed, and the air discharging through the air pipes 43 and the stack 44 to the cowl 45.

The trap tank 17 has a vapor outlet 135 with a vapor pipe 136 connected thereto leading upwardly by a pipe 137 and discharging into the upper part of the air trap 40 as indicated at 138. The condensate of the condensed vapors is discharged through a pipe 139 having a trap 140 therein, this trap having a junction 141 with the pipe 137. Therefore, this vapor connection from the trap tank 17 functions substantially the same as the vapor connections from the tanks 15 and 16, returning the condensed vapors after filling the trap back to the tank 17; and also the vapors which are carried by the air blast in drying the fabrics are returned to this tank 17. It is to be understood that the air is preferably heated during the drying operation of the fabric.

The furnace 24 is provided with a smoke pipe 145 which leads to a stack 146. There is also a connection 147 from a hood 148 which is placed over the still 23. This connection leads to the stack 146 and discharges the heated air collecting in the hood.

A pressure relief system is provided by a pipe 149 leading upwardly from the pipe 88 which is connected to the condensing coil 30. This pipe has a safety valve 150 on the top thereof. The pipe 88 has its connection to the coil 30 by a pipe 151. In addition, the vapor vent pipe 111 has a relief pressure valve 152 preferably located in the cowl 45. The valve 150 is designed to allow excess pressure to blow off the vapors of the liquid being distilled in the still 23, and the valve 152 is designed to allow outflow of vapors on excess pressure in the different condensers and also to allow back flow of air.

From the above description it will be seen that I have developed a comprehensive cleaning apparatus especially designed for textile materials, in which the same cleansing fluid may be used over and over again in cycles, this being first cleansed by passing through the separating trap 22 and then by being distilled and condensed. The dirt and other impurities are eliminated from the storage tanks and should it happen that the liquid on first distilling, that is, the first run from the still, is not sufficiently clear, this may be passed to a trap tank and then pass through the separating trap and back through the still a second time.

It will also be seen that I have developed a comprehensive system of collecting the vapors of the cleansing fluid after evaporating these from the textiles, and that a make provision for blowing first the dust out of the textiles and collecting this and employ heated air which thoroughly dries the articles being handled, after evaporating the cleansing fluid.

From the above description it will be seen that I have developed a comprehensive cleaning apparatus and method in which the material or garments the first blown clean of loose dust and the like, by the air blast under pressure, and after this, subjected to the cleaning action of the cleansing fluid, this being followed by the air blast, preferably heated, which dries and deodorizes the garments, or the like. Also, in this handling of the cleaning operation there are no pumps utilized or similar moving parts, except the action of the valves and

the rotary drum in the cleaning machine. In addition to this, the filter and separating trap 22 catch loose articles, such as buttons, matches, coins, and the like, and a great deal of the sediment is deposited therein, preventing the accumulation of sediment in the still or evaporator.

Various changes may be made in the principles of my invention without departing from the spirit thereof, as set forth in the description, drawings and claims.

I claim:

1. A cleaning apparatus comprising in combination a cleaning machine, means to blow heated air therethrough, a water seal forming a dust collector and a condenser for vapors, means to connect the machine to the water seal or to the said condenser, and a tank to receive the condensate of the condenser.

2. A cleaning machine comprising in combination a supporting structure having a water tank at the top with condensing coils therein, a tank for the run of the still connected to the coils and below the water tank, a clear fluid tank below the run of the still tank, a trap tank, means to connect either the clear or the trap tank to the run of the still tank, a cleaning machine, a gravity connection from the clear fluid tank to the machine, a separating trap, a connection from the machine to the trap, a still, a connection from the trap to the still, and a connection for vapors from the still to the condensing coils in the condensing tank.

3. A cleaning machine, as claimed in claim 2, a second set of condensing coils in the condensing tank, and a connection from the tank for the run of the still to convey vapors therefrom to the second set of coils.

4. A cleaning machine, as claimed in claim 2, a plurality of additional condensing coils in the condensing tank, a connection from the tank for the run of the still and from the clear fluid tank to said coils to convey vapor thereto, the condensate in such coils flowing back to the said tanks.

5. A cleaning machine comprising in combination a condensing tank having a condensing coil therein, a tank for the run of the still connected to said coil, a cleaning machine, means to convey fluid from the tank to the machine, a separating trap, means to convey used fluid from the machine to the trap, a still connected to the trap, a vapor connection from the still to the condensing coils, means to blow air through the cleaning machine, means to convey the blown air from the machine, a vapor trap having a condenser to condense vapors in the air, a trap tank, means to connect said tank to the run of the still tank, a connection from the trap tank to the separating trap, and a vapor connection from the trap tank to the vapor trap and its condenser.

6. In a cleaning apparatus, a cleaning machine, means at the bottom of said machine to blow hot air therein, an outlet at the top for the exhaust air, a water seal and a vapor trap having a condenser, means to divert the air to the water seal or to the condenser, a receptacle for condensed fluids connected to said condenser, a separator trap, means to flow a cleaning fluid into the cleaning machine and the used fluid to the trap, and means to flow the condensate from the air trap to the separator trap.

7. A cleaning plant comprising in combination a cleaning machine, a still, a gravity connection from the machine to the still, a condenser above the still and the machine, a vapor connection from the still to the condenser, an upper tank,

5 a gravity connection from the still to the said tank, a main storage tank, a gravity connection from the upper to the main storage tank, a gravity connection from the tank to the machine, a tank for dirty liquid, a connection from the upper tank to the dirty liquid tank and a connection from the dirty liquid tank to the still.

10 8. A cleaning plant comprising in combination a cleaning machine, a still, a gravity liquid connection from the machine to the still, a first vapor condenser above the machine and the still, a vapor connection from the still to said condenser, an upper tank, a liquid connection from the said condenser to the tank, a main storage tank, a gravity connection from the upper tank to the main tank and from the main tank to the machine, a second condenser, a connection from the upper tank to the second condenser, 15 a third condenser, a connection from the main tank to the third condenser, the liquid condensed in the said second and third condensers returning respectively to the upper and main tanks and a vapor connection from each of the condensers to atmosphere.

20 9. A cleaning plant as claimed in claim 8, a trap tank for dirty liquid, a gravity connection from the upper tank to the trap tank and a gravity connection from the trap tank to the still, an air vapor condensing trap positioned above the trap tank, a vapor connection from the trap tank to the air vapor trap, the condensed liquid flowing backwardly to the trap tank, and a connection to atmosphere from the air 25 vapor trap.

25 10. In a cleaning apparatus, a cleaning machine with means to flow a cleaning fluid into and out of said machine, an air blower connected to atmosphere, a heater, a connection from the heater to the bottom of the cleaning machine, a connection from the top of the cleaning machine to atmosphere and to a water seal receptacle and a valve to control the flow of air to the atmosphere or to the said water seal 30 receptacle.

35 11. In a cleaning apparatus, a tank, a cleaning machine having means to flow a cleaning fluid from the tank to the machine, means to flow fluid from the machine, an air blower drawing air from atmosphere, an air heater, a connection from the heater to the bottom of the machine, an air vapor trap forming a condenser, a connection from the top of the machine to the said trap, a connection from the said trap to atmosphere, a trap tank to receive the condensed liquid from the trap, an air connection from the top of the machine to a water seal receptacle, and a valve to control the flow of air 40

to the air vapor trap or to the water seal receptacle.

45 12. A cleaning apparatus comprising in combination a cleaning machine, a still, a gravity liquid connection from the machine to the still, a condenser above the machine and the still, a vapor connection from the still to the condenser, an upper tank, a gravity liquid connection from the condenser to the tank, a gravity liquid connected from the tank to the machine, an air 50 blower connected to atmosphere, an air heater, a connection from the heater to the bottom of the machine, an air vapor trap separate from the condenser, an air connection from the top of the machine to the said trap, a connection from the trap to atmosphere, and means to return vapor from the trap to the still independent of said upper tank.

55 13. A cleaning apparatus as claimed in claim 12, a water seal receptacle, a connection from the top of the machine to the said receptacle, and a valve to control the flow of air to either the air vapor trap or to the said receptacle.

14. A cleaning plant comprising in combination a cleaning machine, a tower, a still, a gravity connection for the flow of fluid from the machine to the still, a condenser positioned above the still in the tower, a vapor connection from the still to the condenser, an upper tank in the tower for the first run of the still positioned below the condenser and above the still, a fluid connection from the condenser to the said upper tank, a main storage tank in the tower below the upper tank, a gravity connection from the upper to the main tank, and a gravity connection 30 from the main tank to the machine, and a direct connection from the upper tank to the still.

15. A cleaning plant comprising, in combination, a vertical tower structure, a cleaning machine adjacent said tower structure, a separating trap and a still located at the base of the tower structure, a gravity connection from the machine to the trap and from the trap to the still, a condenser positioned adjacent the top of the tower above the cleaning machine, the 40 trap, and the still, a vapor connection from the condenser to the still, an upper tank located in the tower below the condenser, a gravity liquid connection from the condenser to the tank, a gravity connection from the tank to the cleaning machine, a tank for dirty liquid located in the tower below the first mentioned tank, a gravity connection from the first mentioned tank to the dirty liquid tank, and a gravity connection 45 from the dirty liquid tank to the separating trap.

F. E. SNOWDEN.
